UNITED STATES PATENT OFFICE.

ERNEST A. PFLUEGER, OF AKRON, OHIO, ASSIGNOR TO THE E. A. PFLUEGER COMPANY, OF AKRON, OHIO, A CORPORATION OF OHIO.

HARNESS-ROSETTE.

No. 878,893.

Specification of Letters Patent.

Patented Feb. 11, 1908.

Application filed October 2, 1907. Serial No. 395,552.

To all whom it may concern:

Be it known that I, ERNEST A. PFLUEGER, a citizen of the United States, residing at Akron, in the county of Summit, State of Ohio, have invented new and useful Improvements in Harness-Rosettes, of which the following is a specification:

My invention relates to harness ornaments, known as "rosettes," and has for its objects, first, to provide a construction that may be assembled without riveting, and which will present an appearance of thickness and weight without its actual weight being materially increased; and, secondly, to provide a reinforce for the body of the article that will permit the latter to be made of thin metal, and yet will protect the same against indenting or crushing.

These objects I accomplish in the manner and by the means hereinafter described and claimed, reference being had to the accompanying drawings, in which:

Figure 1 is a detail perspective view, partly broken away, of the outer shell. Fig. 2 is a similar view of the wire loop and its connected parts. Fig. 3 is a detail plan view of the washer. Fig. 4 is a central vertical sectional view of the rosette assembled, but with the edge of the outer shell uncrimped. Fig. 5 is a view similar to Fig. 4, but at a right angle thereto, showing the rosette completed.

Similar numerals of reference denote corresponding parts in the several views.

In the said drawing the reference numeral 1 denotes the outer shell of the article, the same being formed from a thin sheet of any suitable metal, and formed, by stamping or otherwise, with its body portion preferably slightly convexed, and with an annular in-turned rim 2 of considerable depth.

The loop 3 of the article is formed of wire, as shown in Fig. 2, and has formed integral therewith the two semicircular arms 4, which are somewhat resilient, and which together form a ring adapted to fit snugly within the rim 2 of outer shell 1, and thus position the loop 3. An inner disk 5, slotted at 6 to pass over the loop 3, and dished sufficiently to rest on the arms 4 when posi-

tioned in the outer shell 1, and yet to contact with, or substantially contact with, the inner surface of said outer shell, as shown in Figs. 4 and 5, completes the article. With the loop 3 and its arms 4 in position within the outer shell 1, and the disk positioned therein by fitting the slot 6 therein over the loop 3, as shown in Fig. 4, the parts are firmly united by turning over and crimping the edge of the rim 2 onto the edge of said disk 5, as clearly shown in Fig. 5, said disk being thus firmly retained in position, and as firmly retaining the arms 4 of loop 3.

It will be seen that, by reason of the dished form of disk 5, the outer edge of the latter will contact with the rim 2 at quite a distance, relatively, from the arms 4, so that, when the rim 2 is turned over and crimped thereon, a substantial thickness will be left to the unturned portion of said rim 2, thereby giving to the article an appearance of bulk and weight without increasing its actual weight. So, also, by employing the dished disk 5 in substantial contact with the inner surface of the outer shell 1 at its center, the indenting of the latter by accidental blows is effectually prevented, thus permitting the use of a thin sheet of metal in the manufacture of said shell.

While I have shown and described the body portion of the outer shell as preferably slightly convexed, it will be understood that I may form the same with a flat surface, or may even form it slightly concaved.

Having thus described my invention, what I claim as new and desire to secure by Letters Patent is:

1. An article of the character described, embodying an outer shell formed with an annular in-turned rim, a ring located within the rim of said shell and carrying a loop, and a disk resting on said ring and apertured to permit the projection therethrough of said loop, said outer shell rim being turned over and crimped onto the edge of said disk.

2. An article of the character described, embodying an outer shell formed with an annular in-turned rim, a ring located within the rim of said shell and carrying a loop, and a dished disk resting on said ring and aper-

tured to permit the projection therethrough of said loop, said disk being at its center in substantial contact with the inner surface of said outer shell and at its edge in contact with said rim at a distance from said ring, and said rim being turned over and crimped onto said disk.

In testimony whereof, I have hereunto set my hand in the presence of two subscribing witnesses.

ERNEST A. PFLUEGER.
